UNITED STATES PATENT OFFICE

JAMES D. LALOR, OF BALTIMORE, MARYLAND, ASSIGNOR TO THE LALOR FUEL OIL SYSTEM COMPANY, INC., OF BALTIMORE, MARYLAND, A CORPORATION OF MARYLAND

APPARATUS FOR FIRING FURNACES WITH FLUENT FUELS

Application filed June 13, 1925. Serial No. 36,862.

This invention is concerned with the use of fluent fuels such as hydrocarbons, gas (either natural or artificial), and powdered coal in firing furnaces of various kinds, as well as with equipment or systems useful for this purpose; the main and underlying object being to enable attainment of homogeneously commingled and assimilated combustible mixtures with such fuels, to the end 10 of securing an absolutely smokeless flame of maximum calorific intensity attended by the utmost economy in fuel consumption, and the highest efficiency in furnace operation.

Although my invention may be practiced 15 with marked advantages in furnace operation generally, its importance is especially manifest in instances of manufacture where an intensely hot smokeless flame is absolutely essential to the insurance of a product free 20 from physical and chemical imperfections. One such instance is in connection with the manufacture of glass, and I have accordingly, by way of example, hereinafter described 25 my invention as applied to a furnace more particularly adapted for making such material. The advantages both general and specific to the exemplification chosen, together with those accruing from novel structural improvements in furnaces and firing 30 apparatus in accordance with my invention, will be readily apparent as the description 35 proceeds.

With reference to the drawings, Fig. I is a 35 plan sectional view of a glass furnace of the recuperative type embodying the improved structural features and firing apparatus of my invention.

Fig. II is a central longitudinal section of the furnace.

40 Fig. III is a detail section, taken as indicated by the arrows III—III in Fig. I.

Fig. IV is a transverse sectional view on a larger scale through the recuperator of the furnace, and taken as indicated by the arrows 45 IV—IV in Fig. I.

Fig. V is an illustration, partly in elevation and partly in section, of the atomizing burner for oils shown in connection with Figs. I and II.

50 Fig. VI is a fragmentary sectional view

of the discharge end of the burner, this illustration being on a larger scale than that of the preceding figure.

Fig. VII is an end view of one of the components of the fuel atomizing nozzle of the 55 burner aforesaid; and

Fig. VIII is a detail sectional view of a swivel joint which I employ in the pipe line whereby the fuel is conducted to the atomizer.

The glass furnace herein shown is generally 60 of standard construction in that it comprises an elongated horizontal arch-roofed fusing chamber or "tank" 1 with a transversely-extending dam 2 adjacent its rounded front or delivery end 3, and an opening 4 in one of its 65 side walls for convenience in introducing the ingredients which are to be converted into glass. Forming a part of the furnace and extending laterally of the opposite or rear end of the tank 1, is a recuperator 5 with a series 70 of horizontal flow passages 6 for the spent hot gases resulting from combustion, which afford a series of relatively-isolated cross-communicating intervening spaces 7 through 75 which the air used to support combustion passes in a general upward direction, and is incidentally preheated enroute to the tank 1, is a well known manner. The spent gases leave the fusing chamber or tank 1 by a passage shown at 8, and enter the top of 80 the recuperator 5 wherein they pass back and forth as indicated by the arrows in Fig. IV, and as determined by baffles 9 at opposite sides of the structure, said gases finally making their exist, through a passage 10 near 85 the bottom, into a flue or stack, not shown. The air used to support combustion is, in the present instance, supplied under pressure 90 by a blower 11 from which extend a pair of trunk conduits 12 that extend along opposite sides of the recuperator 5, as shown in Figs. I and II; each of said conduits terminating in a multiplicity of outlet branches 13. By this arrangement, the air supply is uniformly distributed to the spaces 14 in the 95 bottom of the recuperator 5—Figs. II and IV—for upward flow through the spaces 7, aforesaid. The trunk conduits 12 are each equipped with a suitable valve 12a, while the branches 13 are likewise individually pro-

100

vided with adjustable gates 15 permitting regulation of the air supply as may be required, in initially securing the proper proportioning. After being preheated in the recuperator 5, the air leaves the chamber 16, in the top of the latter, by an upwardly-sloping passage 17 which terminates in a constricting space or ante-chamber 18, see Figs. I and III, formed so as to induce swirling of the air, together with fluent fuel through an inwardly tapering orifice 19 in the end wall 20 of the tank 1, as later on more fully described.

As a means to inject the fluent fuel into the furnace, I conveniently employ the burner shown in Figs. V, VI and VII, but other forms thereof may be adapted thereto, depending on the kind of fuel which is to be used. The burner of Figs. V, VI and VII, is adapted for consumption of oils, and since it is illustrated in the complete furnace organization, shown in Figs. I-IV, and therein designated generally by the numeral 21, I will now describe its details and operation. As shown, this burner 21 comprises a long tubular body 22 which is held in a sleeve 23 adjustably secured to an upstanding bracket 24 on the top of the recuperator 5 between the walls of the passages 8 and 17, see Figs. I and II. The burner 21 is thus supported at the proper elevation in alignment with the opening 19, and with its front or nozzle end projecting through a replaceable apertured block 25 of suitable refractory material let into the transverse outer wall 26 of the air passage 18 so as to discharge the vaporized fuel across said passage into the tank 1. Atomizing air is conducted to the burner 21 through a pipe elbow 27 at its rear end, said elbow affording connection with a depending branch of an overhead conduit 28 which extends from a high pressure blower shown at 29, Fig. II. Interposed in the conduit 28 at a point convenient of access, is a suitable gate valve 30 whereby the atomizing air flow to the burners 21 may be suitably regulated. The conduit 28 has also interposed in it, a joint connection 31, which, in practice, is made so as to be readily separable for a purpose later disclosed herein.

Hydrocarbon fuel is supplied to the burner 21 under comparatively high pressure, by a suitable pump from a storage tank, neither of these elements being shown, by a pipe line 32. Associated with this pipe line 32—Fig. II—are necessary or desirable auxiliaries such as a hand control valve 33, an automatic safety drain valve 34, a strainer 35, and an adjustable pressure control device 36. The branch 37 of the fuel line 32 extending down to the burner 21, embodies a number of component sections 38 that are interconnected by means of swivel joints such as shown at 39 in Fig. VIII. Each such joint 39 includes a stuffing box fitting 40 that is attached to the end of one pipe component, and telescopically

receives a lateral tubular extension 41 on the contiguous end of the connecting component. The tubular member 41 is flanged at 42 so as to be held against withdrawal from the fitting 40, a plug 43 closing the end of said fitting, enabling ready insertion of the member 41 when initially assembling the joint 39. Upon breaking the connection 31 in the air conduit 28, it will be apparent that the burner 21 may, when necessary, be easily withdrawn from the apertured block 25 for cleaning the nozzle end thereof, simply by longitudinally sliding said burner in the sleeve 23, the swivel joints 39 allowing this movement. The burner 21 is thus made accessible, for the purpose noted, without requiring disconnection of the fuel line 32, thereby obviating contention with leaking connections as would otherwise result after a few repetitions of this operation. Again referring to Fig. V, it will be noted that the tubular body 22 of the burner 21 encloses a coextensive co-axial tube 45 that conducts the liquid fuel to the atomizing nozzle, said tube being connected to the fuel line 32 at the rear end and having interposed at this juncture, a hand valve 46 whereby the flow may be accurately regulated. As shown, the tube 45 is of considerably smaller diameter than the tubular body 22, and a comparatively large annular space 47 is thus left through which the atomizing air is conveyed or directed to the nozzle. As shown to better advantage in Fig. VI, an enlargement 48 at the front end of the tube 45 affords a cavity that is internally threaded to take a part 49 constituting the tip of the nozzle, said tip having a minute axial orifice 50 with a divergent exit flare 51. The hollow of the inwardly projecting portion of the tip 49 is tapered as at 52 and formed with a small circular counter recess 53 that is concentric with the orifice 50. Within the hollow of the tip 49 is located a core piece 54, shown as being somewhat reduced in diameter through a portion of its length as indicated at 55, and circumferentially enlarged at one end as at 56, to a diameter corresponding substantially to that of the cavity in the extremity 48 of the tube 45. The opposite end of the core piece 54 is fashioned to frusto-conical configuration, to coincide accurately with the conical internal surface 52 of the tip 49. A compressible washer 57 is interposed behind the core piece 54 to hold it firmly against endwise movement and to insure firm and snug pressure contact between the contiguous conical surfaces at 52. The flat lateral end of the truncated portion of the corepiece 54 forms jointly with the counter bore recess 53 of the tip 49, a closed circular chamber. This circular chamber is approached from the annular space 58 surrounding the smaller portion 55 of the core piece 54, by way of a number of tangentially disposed channels 130

afforded by grooves 59 in the conical surface of said core piece 54, see Fig. VII. The annular space 58 is in turn approached by cross branches of an axial duct 60 in the core piece 54 which duct registers with the opening 61 in a transverse partition of the tube 45, the main bore of the latter housing an insert 62 having a spiral groove 63 for the liquid fuel. When the burner 21 is properly positioned, as shown in Fig. V, the projecting portion of the tip 49 engages the opening in a central hub boss of a device 64 with radially-disposed angularly-pitched vanes 65. This vaned device 64 is screwed into a ring coupling 66 at the outer end of the tubular body 22 of the burner 21. A second annular threaded coupling 67 serves to secure a centrally apertured disk 68 in a manner enabling ready adjustment of the space 69 between it and the vaned device 64. The area of the aperture 70 in the disk 68 relative to the internal area of the coupling 67 is about one-fourth of the latter.

The operation of the furnace equipped with the burner 21 is as follows: The fluid fuel fed to the burner 21 under high pressure is obliged to travel the comparatively long spiral groove 63 defined by the insert 62 in the tube 45, and is incidentally raised in temperature by virtue of the passage of preheated atomizing air through the annular space 47 at the same time. After traversing the spiral groove 63 within the tube 45, the liquid, now sufficiently warmed for facilitation of the atomizing process which is to follow, passes through the opening 61—Fig. VI—directly into the annular space 58, by way of the branched duct 60 in the core piece 54. As a consequence of forced passage through the tangentially-disposed channels 59 of the core piece 54, the liquid is rapidly rotated in the small circular chamber 53, and incident to expulsion through the minute orifice 50 in the tip 49 under high velocity, is effectively atomized and issues as a spirally-swirling spray. At the same time, it encounters a stream of preheated atomizing air rotating in the space 69 due to forced passage through the vaned device 64. The convergent form of the aperture 70 in the disk 68 promotes mechanical interaction between the atomizing air and the fuel within the space 69 so that the spray is further broken up and finally discharged, at accelerated velocity, in a spirally-advancing thoroughly atomized condition. Referring again to Figs. I and II the thoroughly atomized fuel crossing the terminal portion 18, of the air passage 17 from the recuperator 5, is encountered by the combustion-supporting air, swirling as already explained. By enforced commingling of the thoroughly atomized liquid fuel and air, a very homogeneous highly-combustible mixture is assured, the same being injected through the orifice 19 directly into the tank 1. By virtue of the

whirling impetus given the combustible mixture, I secure—as conventionally indicated by dotted lines in Figs. I and II—a progressively-expanding, spirally-rolling flame, which, after passing along one side of the tank 1, is re-directed by the rounded end 3 in the opposite direction along the other side of the tank 1 for escape of the spent gaseous products of combustion into the passage 8 leading to the recuperator 5, the flame being incidentally depressed by the deflecting action of the arched roof of the tank 1 so that the contents beneath are uniformly subjected to the action of the heat. By proper regulation of the various instrumentalities provided in the fuel and air lines 32, 28, the pressure and proportioning of the mixture may, obviously, be very accurately regulated and a white-hot smokeless flame obtained that is of extremely high calorific intensity and at such velocities which best suit the various exigencies of practice. It will be apparent that heavy fuel oils may be effectively atomized and carburized for the purposes set forth.

Having thus described my invention, I claim:

1. In a recuperative furnace, the combination of a burner including means to effectively atomize fuel, a vaned member in said burner adapted to discharge atomizing medium with rotary motion so that the atomized fuel is emitted from the burner tip under spirally-flowing action, and means having a spiraled outlet for concurrently discharging air with whirling progressively-expanding flow to support combustion in the furnace.

2. A recuperative furnace embodying an ante-chamber with a constricting spiral section and inwardly tapering outlet, a burner including devices adapted to effectively atomize liquid fuel under rotary action, said burner being positioned to discharge the atomized fuel across the constricting spiral section, and means supplying combustion-supporting air under pressure to the ante-chamber for intimate commingling therein with the discharging atomized fuel and concurrent ejection through the tapering outlet aforesaid into the furnace.

3. In a recuperative furnace, the combination of a burner including aligned devices adapted to effectively atomize liquid fuel for discharge with a spirally advancing motion, and a spirally-formed ante-chamber in the recuperator section of the furnace into which the nozzle of the burner projects and through which preheated combustion-supporting air flows under pressure and is thereby whirled for spiral progressively-expanding advancement into the furnace concurrently with the vaporized fuel.

4. In a recuperative furnace, the combination of a burner including axially aligned devices adapted to effectively atomize liquid fuel for discharge with spirally-expanding

flow into the furnace, and a passage forming a part of the recuperative section for conducting preheated combustion-supporting air under pressure into said furnace, said passage embodying a constrictive volute spiral terminus adapted to induce whirling of the combustion-supporting air for spiral progressively-expanding advancement into the furnace concurrently with the commingling atomized fuel.

In witness whereof, I have hereunto signed my name at Philadelphia, Pennsylvania, this 4th day of June, 1925.

JAMES D. LALOR.
